US00D692059S

(12) United States Design Patent
Chen et al.

(10) Patent No.: US D692,059 S
(45) Date of Patent: * Oct. 22, 2013

(54) VENDING MACHINE

(75) Inventors: Yun-Lung Chen, New Taipei (TW);
Chung Chai, New Taipei (TW);
Chang-Ru Xu, Wuhan (CN)

(73) Assignee: Hon Hai Precision Industry Co., Ltd.,
New Taipei (TW)

() Term: 14 Years

(21) Appl. No.: 29/418,943

(22) Filed: Apr. 24, 2012

(30) Foreign Application Priority Data

Apr. 16, 2012 (CN) 2012 3 0111320

(51) LOC (9) Cl. 20-01

(52) U.S. Cl.

USPC D20/4

(58) Field of Classification Search

(57) CLAIM

The ornamental design for a vending machine, as shown and described.

DESCRIPTION

FIG. 1 is a perspective view of the vending machine showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures form no part of the claimed design and the shade lines in the figures show contour and not surface ornamentation.

1 Claim, 7 Drawing Sheets
